UNITED STATES PATENT OFFICE.

STEPHEN E. ATTEBERY AND CHESTER GILES, OF MACON, ILLINOIS.

WINDOW-SHADE FIXTURE.

SPECIFICATION forming part of Letters Patent No. 770,252, dated September 20, 1904.

Application filed April 5, 1904. Serial No. 201,659. (No model.)

To all whom it may concern:

Be it known that we, STEPHEN E. ATTEBERY and CHESTER GILES, citizens of the United States, residing at Macon, in the county of 5 Macon and State of Illinois, have invented certain new and useful Improvements in Window-Shade Fixtures, of which the following is a specification, reference being had therein to the accompanying drawings.

10 This invention relates to an improvement in combined shade and curtain brackets; and its object is to provide a combined shade and curtain bracket which can be adjusted to various-sized windows and which can be readily 15 detached from or attached to the window-frame without the use of screws, nails, or other similar fastening means.

In the drawings, wherein a preferable embodiment of our invention is shown, and 20 wherein like letters of reference refer to similar parts in the several views, Figure 1 is a perspective view of our combined shade and curtain bracket secured to the window-frame. Fig. 2 is a perspective view of the 25 bracket, showing the fastening-lever in its open position. Fig. 3 is a transverse section through the bracket and the fastening-lever when the same is in its lowermost position.

Referring now more particularly to the 30 drawings, A and A' are two bars which are slidably connected at their inner ends and which are adapted to be secured to and extend entirely across the window-frame. The outer ends of the rods A and A' are bent at 35 substantially right angles to form the pieces a and a', which contain, respectively, the aperture a² and the open-ended squared slot a³, which are adapted to receive the squared and round ends of the ordinary shade-roller.

40 B and B', which are the brackets for supporting the curtain-rod, are pivotally secured to the outer side of the pieces a and a' in rear of the aperture a² and the slot a³. The brackets B and B' are each provided at their lower 45 edges with the open-ended slots b and b', which when the brackets are lowered are arranged to straddle the ends of the shade-roller which project through the aperture a² and the slot a³ in pieces a and a'. It will 50 therefore be seen that the curtain-brackets B

and B' form a means for locking the shade-roller in the pieces a and a', as it cannot be removed therefrom until the brackets B and B' are raised from off of the projecting ends of the shade-roller. The brackets B and B' 55 are preferably formed of sheet metal and have formed at their rear ends the substantially U-shaped portions b² and b³, which are arranged to straddle the pieces a and a'. It will be apparent that when the brackets B 60 and B' are lowered on their pivots the top of the U-shaped portions b and b' will rest on the upper edge of the pieces a and a' and limit the downward movement of said brackets.

C and C' are brackets secured to the rear 55 face and at the outer ends of the bars A and A'. These brackets are preferably made of sheet metal and are formed with the arms c and c', which are arranged to lie alongside of the rear face of the bars A and A', and 70 the rearwardly-extending arms c² and c³, which extend at substantially right angles to the arms c and c'. Both the arms c and c' and the arms c² and c³ are provided with longitudinal slots therein extending almost their entire length. The brackets C and C' are 75 adjustably secured to the bars A and A' by means of bolts or screws c⁴ and c⁵, which pass through the slots in the arms c and c' and engage threaded apertures in the ends of said 80 arms A and A'. Thumb-nuts of any desired type are secured upon the projecting ends of the bolts. The upper and lower edges of the arms c and c' are bent at substantially right angles to form flanges, which overlie and underlie 85 the upper and lower edges of the bars A and A', which prevent the brackets from turning on the locking-bolts.

D and D' are feet which are adjustably secured to the arms c² and c³ of the brackets C 90 and C' by means of bolts or screws d and d', secured therein, and which project through the slots in said arms. Thumb-nuts d² and d³ are secured upon the projecting ends of the bolts d and d'. The upper and lower edges of 95 the arms c² and c³ are bent at substantially right angles, so that they will overlie and underlie the upper and lower edges of the feet D and D'. The outer ends of the feet D and D' are bent outwardly at substantially right 100

angles to form the pieces d^4 and d^5 , which embrace sides of the window-frame when the device is attached thereto.

The arms A and A' are each provided at 5 their inner ends with the longitudinal slots a^2 and a^3 . The arms are also slidably connected to each other by an upwardly-extending loop a^7 , secured to the inner end of the arm A and encircling the arm A', and a downwardly-extending loop a^6 extending from the inner end 10 of the arm A' and encircling the arm A. The loops a^4 and a^5 are made slightly wider than the arms A and A', so that said arms may have a slight lateral play therein as well as a 15 longitudinal movement therethrough. E is a lever interposed between the overlapping portions of the ends of the arms A and A'. Loosely secured in opposite sides of one end of the lever are the bolts e and e' , which project through the slots a^4 and a^5 in the arms A and A'. Thumb-nuts e^2 and e^3 are secured to the projecting ends of the bolts e and e' . A 20 handle e^4 is secured to the under edge of the lever E for operating the same. The projecting ends of the bolts e and e' are made slightly 25 smaller in diameter than the portions of the bolts which lie within the lever E to form shoulders against which the washers e^5 abut when the nuts e^2 and e^3 are tightened, thereby 30 preventing the lever from being clamped between said washers when said nuts are tightened. From the above description it will be seen that by loosening the nuts e^2 and e^3 the inner ends of the arms A and A' may be made 35 to overlap to a greater or less extent to permit of the use of the device on narrow or wide window-frames.

Having described the construction of our improved shade and curtain bracket, we will 40 now describe the manner of applying the same to a window-frame.

The lever E is first moved, by means of the handle e^4 , as far to the right as possible, which will, through the bolts e and e' , cause the bars 45 A and A' to move inwardly in opposite directions. The brackets C and C' are then adjusted so that the distance between the feet D and D' is substantially the same as the distance between the sides of the window-frame 50 to which the device is to be attached. The feet D and D' are then adjusted on the arms c and c' of the brackets C and C' until they are wide enough to embrace the sides of the window-frame. With the parts in this position 55 the device is placed in the window-frame and the lever E is swung around to the left until it lies between the overlapping ends of the arms A and A'. This movement of the lever will, through the bolts e and e' , cause the 60 bars A and A' to be moved outwardly in opposite directions, and this movement of the arms A and A' will cause the feet D and D' to bind firmly against the sides of the window-frame and hold the device securely therein. 65 To detach the device from the window-frame,

it is only necessary to take hold of the handle e^4 and move the lever E as far to the right as possible, when the feet D and D' will be withdrawn from contact with the sides of the window-frame.

70

Having thus described our invention, what we claim as new, and wish to secure by Letters Patent, is—

1. A device of the character described comprising a pair of bars carrying curtain-brackets, means secured to the bars for engaging a window-frame when the bars are moved in opposite directions, and a lever having an adjustable pivotal connection with both of said bars.

75

2. A device of the character described comprising a pair of bars having their inner ends overlapped, straps secured to the inner end of each of the bars and encircling the adjacent bar, a pair of curtain-brackets carried by the bars, means secured to the bars for engaging a window-frame when the bars are moved in opposite directions, and a lever interposed between the overlapping portions of the bars and having a pivotal connection with each of 90 said bars.

80

3. A device of the character described comprising a pair of bars having their inner ends overlapped, straps secured to the inner end of each of the bars and encircling the adjacent bar, a pair of curtain-brackets carried by the bars, means secured to the bars for engaging a window-frame when the bars are moved in opposite directions, and a lever interposed between the overlapping portions of the bars 100 and having an adjustable pivotal connection with each of said bars.

95

4. A device of the character described comprising a pair of bars having their inner ends overlapped, straps secured to the inner end of each of the bars and encircling the adjacent bar, a pair of curtain-brackets carried by the bars, devices adjustably secured to the bars and arranged to engage a window-frame when the bars are moved in opposite directions, and a lever interposed between the bars and having a pivotal connection with each of said bars.

105

5. A device of the character described, comprising a pair of bars in slidable engagement with each other, a pair of curtain-brackets carried by said bars, a pair of angle-brackets having one arm adjustably connected to the rear face of each of said bars and the other arm projecting at substantially right angles therefrom, a pair of feet adjustably connected to the projecting arms of said brackets, said feet being arranged to engage the sides of a window-casing when the bars are moved in opposite directions, and means for adjustably connecting the inner ends of the bars.

110

6. A device of the character described, comprising a pair of bars in slidable engagement with each other, a pair of curtain-brackets carried by said bars, a pair of angle-brackets having one arm adjustably connected to the 120

rear face of each of said bars and the other arm projecting at substantially right angles therefrom, a pair of feet adjustably connected to the projecting arms of said brackets, said 5 feet being arranged to engage the sides of a window-casing when the bars are moved in opposite directions, and a lever having a pivotal connection with each of said bars.

7. A device of the character described, comprising a pair of bars in slidable engagement with each other, a pair of curtain-brackets carried by said bars, a pair of angle-brackets having one arm adjustably connected to the rear face of each of said bars and the other 15 arm projecting at substantially right angles therefrom, a pair of feet adjustably connected to the projecting arms of said brackets, said feet being arranged to engage the sides of a window-casing when the bars are moved in opposite directions, and a lever having an adjustable pivotal connection with each of said bars.

8. A device of the character described comprising a pair of slotted bars carrying curtain-brackets, means secured to the bars for engaging a window-frame when the bars are moved in opposite directions, a lever, a pair of bolts loosely mounted in the lever and projecting through the slots in the bars, and 30 means for adjustably securing the bolts in the slots.

9. A device of the character described comprising a pair of bars having their inner ends slotted and overlapped, straps secured to the 35 inner end of each of the bars and encircling the adjacent bar, a pair of curtain-brackets carried by the bars, means secured to the bars for engaging a window-frame when the bars are moved in opposite directions, a lever in- 40 terposed between the overlapping portions of the bars, a pair of bolts loosely mounted in opposite sides of the lever and projecting through the slots in the bars, and nuts secured on the projecting ends of said bolts.

45 10. A device of the character described comprising a pair of bars having their inner ends

slotted and overlapped, straps secured to the inner ends of each of the bars and embracing the adjacent bar, a pair of curtain-brackets carried by the bars, a pair of angle-brackets having one arm adjustably connected to the rear face of each of the bars and the other arm projecting at substantially right angles therefrom, a pair of feet adjustably connected to the projecting arms of said brackets, said feet 55 being arranged to engage a window-frame when the bars are moved in opposite directions, a lever interposed between the overlapping portions of the bars, a pair of bolts journaled loosely in opposite sides of the lever and projecting through the slots in the bars, and nuts secured on the projecting ends of the bolts.

11. A device of the character described comprising a bar arranged to be secured across 65 the window-frame, a pair of shade-brackets carried by said bar, said shade-brackets being provided one with an aperture and the other with an open-ended angular slot, a shade-roller mounted within said brackets, the ends 70 of the shade-roller projecting without the aperture and slot in the brackets, and a pair of curtain-brackets pivotally secured to said shade-brackets, the lower edges of said curtain-brackets being provided with notches arranged to straddle the projecting ends of the shade-roller when the curtain-brackets are 75 lowered.

12. In combination with a shade-bracket, provided with an aperture therein a curtain-bracket pivoted to said shade-bracket and provided on its lower edge with a slot arranged to register with the aperture in the shade-bracket when the curtain-bracket is lowered.

In testimony whereof we affix our signatures 85 in presence of two witnesses.
